SPECIFICATION forming part of Design No. 30,704, dated May 2, 1899.

Application filed April 4, 1899. Serial No. 711,746. Term of patent 14 years.

To all whom it may concern:

Be it known that I, GEORGE S. HENSEL, a citizen of the United States, residing in the city and county of Philadelphia, State of Pennsylvania, have invented and produced a new and original Design for a Combined Skirt and Shoe Protector, of which the following is a specification, reference being had to the accompanying drawings, forming a part thereof.

The leading feature of my design for a combined skirt and shoe protector is, first, the representation of a fluffy ridge on the side or face of the head thereof, and, next, a head having the representation of a fluffy ridge on the side or face of the same and a brush pendant from the lower edge thereof.

In the drawings, A designates a head, and B designates a brush pendent from the lower edge thereof.

C designates a fluffy ridge on the face of said head, the same extending in the longitudinal direction thereon.

Having thus described my invention, what I claim as new, and desire to secure by Letters Patent, is—

The design for a combined skirt and shoe protector substantially as shown and described.

GEORGE S. HENSEL.
